DESIGN FOR A PICTURE FRAME

Edgar H. Goff, Hilton, Va.

Application September 11, 1945, Serial No. 122,013

Term of patent 14 years

(CL. D29—20)

To all whom it may concern:

Be it known that I, Edgar H. Goff, a citizen of the United States and resident of Hilton Village, in the county of Warwick and State of Virginia, have invented a new, original, and ornamental Design for a Picture Frame, of which the following is a specification, reference being had to the accompanying drawing, forming a part thereof.

In the drawing:

Fig. 1 is a front elevational view of a picture frame, showing my new design;

Fig. 2 is a rear elevational view;

Fig. 3 is a side elevational view; and

Fig. 4 is a top plan view of the same.

I claim:

The ornamental design for a picture frame, as shown.

EDGAR H. GOFF.
